UNITED STATES PATENT OFFICE

104,194

DESIGN FOR A CANDLESTICK

William F. Liska, Chicago, Ill., assignor to Holland Brass Works, Incorporated, Chicago, Ill.,
a corporation of Illinois

Application February 20, 1937, Serial No. 67,915

Term of patent 7 years

To all whom it may concern:

Be it known that I, William F. Liska, a citizen of the United States, residing at Chicago, in the county of Cook and State of Illinois, have invented a new, original, and ornamental Design for a Candle Stick, of which the following is a specification, reference being had to the accompanying drawing, forming a part thereof.

Referring to the drawing:

The figure is a view in perspective showing
my new design for a candle stick.

I claim:

The ornamental design for a candle stick, as shown.

WILLIAM F. LISKA.
